HORS D'OEUVRES PLATE OR SIMILAR ARTICLE

Carlo Stringa, Nove-Vicenza, Italy, assignor to Pitman-Dreitzer & Co., Inc., New York, N. Y., a corporation of New York

Application December 22, 1955, Serial No. 39,439

Term of patent 14 years

(Cl. D44—15)

I claim:

The ornamental design for an hors d'oeuvres plate or similar article, substantially as shown.
